COMPRESSED FLUID CIRCUIT BREAKER
WITH MULTIPLE BREAKSAndré Clerc, Villeurbanne, France, assignor to
Ateliers de Constructions Électriques de Delle,
Paris, FranceApplication November 16, 1934, Serial No. 753,341
In Germany December 18, 1933

11 Claims. (Cl. 200—143)

Circuit-breakers are known in which the arc at break is blown by a compressed fluid directed transversally to the direction of the displacement of the movable contact. My prior American Patent No. 1,961,475 refers to a circuit-breaker of this type in which one of the contacts is connected to an extremity electrode and the other to a second electrode, these two electrodes being fixed behind the contacts and disposed one behind the other preferably in the axis of the extinguishing blast. This device gives good results when operating with medium voltages. With such voltages the single break is quite effective for the reason that the distance between the two electrodes which is determined by the restriking voltage is relatively small and admits the use of an extinguishing chamber of normal height. Further the extremity electrode being disposed at no great distance from the contacts and from the blast pipe, the extinguishing blast is sufficiently effective to drive away the gases formed by the arc.

However, as soon as the voltage exceeds a certain value, the extinguishing chamber becomes very long, the distance between electrodes too great and the exterior electrode as well as that portion of the arc near this electrode are insufficiently swept by the extinguishing blast.

The present invention remedies these disadvantages by converting the above referred to type of apparatus into circuit-breakers provided with multiple breaks. The said invention relates to electric circuit-breakers in which one or several arcs produced at break are blown transversally by means of a compressed fluid against one or several systems of auxiliary electrodes electrically connected together and disposed in the zone of the extinguishing blast where they are juxtaposed to main contacts (or electrodes) and situated behind the latter considered in the direction of the blast. The invention is characterized in that at least two auxiliary electrodes electrically connected together are disposed side by side and juxtaposed to two opposed main contacts (or electrodes) of the circuit-breaker, in such manner that the arc produced at break is divided into at least two separate arcs, each such arc having its points of origin on a main contact and on an auxiliary electrode.

In this manner the arc or arcs initially disposed transversally to the extinguishing blast are each transformed into at least two approximately straight arcs in parallel direction to said extinguishing blast, these arcs being in series but separated one from the other by the elec-

trical connections provided between the various auxiliary electrodes.

The annexed drawings show diagrammatically several embodiments of the object of the invention in which air constitutes the compressed extinguishing fluid. 5

Figs. 1 to 3 show three diagrams of circuit-breakers with a single system of auxiliary electrodes.

Figs. 4 to 6 show in section two other embodiments with a single system of auxiliary electrodes, Fig. 5 being a section through XYX in Fig. 4. 10

Figs. 7 to 9 show three embodiments of circuit-breakers provided with two systems of auxiliary electrodes. 15

Finally Figs. 10 and 11 show two alternative systems of auxiliary electrodes.

For the sake of simplicity, Figs. 1 to 3 and 7 to 8 only show the elements which carry the electric current, the chimneys and conduits for the extinguishing blast being eliminated. 20

In all these figures the various fixed contacts have been designated by A, A¹, A² and the movable contacts by B, B¹, B². The single system of auxiliary electrodes of Figures 1 to 6 bears the reference C and the different electrodes of this system disposed in the zone of the blast are designated by C¹, C², C³. In similar manner, in Figures 7 to 9 the second system of auxiliary electrodes is indicated by D and its electrodes by D¹ and D². 25

The closed position of the contacts is indicated by dash and dot lines, and their open position by full lines. The direction of the blast is indicated by vertical arrows. 35

The resistances inserted in the circuit of the arc when the circuit-breaker is opened are designated by E¹, E², E³.

The electrodes directly connected to the contacts A and B and juxtaposed to the auxiliary electrodes of systems C and D are designated by F¹ and F². 40

The intermediary electrodes disposed between contacts A or B or their electrodes F on the one hand and the auxiliary electrodes of systems C or D on the other hand are designated by G¹ and G². 45

The chimneys surrounding the arcs developed between the auxiliary electrodes of systems C or D on the one hand and the contacts or electrodes AE or F on the other hand bear the references H¹, H², H³ . . . The blast pipes conducting the compressed fluid into the chambers H are indicated by J¹, J², J³ and the common feeding duct 50

55

for the various blast pipes of a circuit-breaker bears the reference K.

Finally, the cooling devices provided at the outlet of chimneys H and indicated diagrammatically in Figures 4 to 6 and 9 are indicated by L¹, L², L³ . . .

The operation of the various devices shown is as follows.

In the device shown in Fig. 1 in which the 10 auxiliary electrodes C¹ and C² of a single system C are juxtaposed to the contacts A and B from which they are entirely insulated, the arc under the influence of the blast first assumes the curved shape shown by the line a. The arc then reaches 15 the auxiliary electrodes C¹ and C² and is thus transformed into two independent arcs b and c parallel to the extinguishing blast, in series with the contacts and separated one from the other by the heavy resistanceless conductor C. The two 20 arcs b and c being disposed parallel to the stream lines of the blast are easily extinguished by the latter.

It sometimes happens that whilst the arc a which under the influence of the blast is curved 25 towards the auxiliary electrodes C¹ and C², is still at a certain distance away from the latter, the space between these electrodes and the contacts A and B is so highly ionized by the gases of arc a that a commutation phenomenon of the arc a 30 into the two arcs b and c takes place before an actual contact of the arc a with the electrodes C¹ and C²; under these circumstances the arc a extinguishes itself without having come in contact with these electrodes and the extinction of 35 the arcs b and c then takes place as indicated above.

In the device shown in Fig. 2, the electrodes C¹ and C² are each juxtaposed to one of the movable contacts B and B¹, a conjuncting conductor M being provided between these contacts. The operation 40 is the same as that described for the preceding device. The arcs BM and MB¹ are curved and come into contact with electrodes C¹ and C². Being short-circuited the inner branches d and e of the arcs are extinguished and the two arcs 45 f and g which correspond to the arcs b and c in Fig. 1 only subsist. In the event of heavy ionization of the spaces B, C¹ and B¹, C² the above referred to commutation phenomenon takes place.

In the device shown in Fig. 3 two movable contacts B¹ and B² traverse in opposite directions two electrodes or conjuncting members M¹M² so as to develop three arcs. To these electrodes are juxtaposed the three auxiliary electrodes C¹, C², C³ of a system C insulated from the contact and electrodes. Under the influence of the transverse blast the three curved arcs reach the electrodes or are commutated onto same. The middle curved arc is first extinguished and is followed by the extinction of the other two arcs.

60 In the three embodiments described, the system of auxiliary electrodes C is supposed to be entirely insulated from the contacts. However, the system C may also be connected electrically to one of the contacts, preferably by a resistance E as shown in chain-dotted lines in Fig. 1. In this case, the resistance is inserted into the circuit and after having accelerated the extinction of the shunted arc (arc C in Fig. 1 for example) it then accelerates the extinction of the arc or arcs with 65 which it is then connected in series.

From the electrical point of view, the circuit-breaker in accordance with Figs. 4 and 5 resembles the diagrams of Figs. 1 and 2. It however differs in that it is provided with fixed electrodes 70 F¹ and F² each connected to one of the contacts

A B and juxtaposed to the auxiliary electrodes C¹ and C² of system C. On the other hand, system C is entirely insulated from the contacts A B and from the electrodes F¹F² as is the case in Fig. 2, however between these latter electrodes and the auxiliary electrodes C¹C² intermediary electrodes G¹ and G² each connected to one of the contacts through the resistances E¹ and E² have been provided.

From the pneumatic point of view, this circuit-breaker differentiates itself from the diagrams of Figs. 1 and 2 in that the two auxiliary electrodes of system C are each disposed in the centre of a distinct chamber H, each of these chambers being fed by a blast pipe J. The two blast pipes J¹ and J² are fed from the common conduit K.

In this device, the arc struck at break between A and B is curved by the extinguishing blast; each of its extreme portions driven against the electrodes F¹ and F² penetrates into one of the chimneys H¹ and H² whereas its central portion is held back by the central partition disposed between the two blast pipes J¹J². The single arc thus assumes the shape of the two arcs shown in Fig. 2 and its various sections are extinguished as described above with the sole difference that as a consequence of the shunting of sections F¹G¹ and F²G² by the resistances E¹, E² the arcs F¹G¹ and F²G² are extinguished before the remaining sections G¹C¹ and G²C². The insertion of these resistances reduces the intensity of the subsisting arcs and this facilitates their extinction.

It is to be noted that to facilitate the penetration of the initial arc into the two chambers H¹H², the central partition between the two blast pipes is provided with a slot N disposed in the plane in which the arc is blown.

Instead of providing two entirely separate chimneys H as in the devices of Figs. 4 and 5, in certain embodiments it is sufficient to separate by means of a vertical partition the two halves of the system C.

The circuit-breaker in accordance with Fig. 6 only differs from the preceding device by the fact that only one shunting resistance is made use of. This resistance instead of connecting one of the contacts with an auxiliary electrode, connects the contact directly with the system C. The arc consequently assumes the same shapes as in the preceding circuit-breaker with the exception that after the introduction of the resistance it is the arc C¹F¹ which is entirely extinguished thereby throwing this resistance in series with the arc C²F². This latter arc being weakened by the insertion of the resistance is rapidly extinguished by the blast.

In the three circuit-breakers shown in Figs. 7, 8 and 9 two systems C and D are provided each of which possessing two auxiliary electrodes C¹—C² and D¹—D².

In the embodiment shown in Fig. 7 the two systems of auxiliary electrodes are insulated from the contacts. In the circuit-breaker shown in Fig. 8 the system C is insulated and the system D connected by the two resistances E¹E² to the contact B² on the one hand and on the other to the conjuncting member M disposed between the two contacts D.

In Fig. 9, the system D is connected in the same manner as in Fig. 8, but in this case the system C is also connected to the movable contact through the resistance E³.

In the three Figs. 7, 8 and 9, the two initial arcs being blown transversely are consequently transformed into four straight arcs all connected in series.

In the device shown in Fig. 7, the four arcs F^1-C^1 , C^2-M^2 , M^1-D^1 and D^2-F^2 are extinguished by the blast without being shunted. In the circuit-breaker shown in Fig. 8, two arcs are entirely shunted and the arc F^1-C^1 is only partially shunted; by the extinction of these three arcs the three resistances are connected in series with the arcs G^1-C^1 , and C^2-M^2 which are subsequently extinguished.

10 In the device shown in Fig. 9 three arcs are entirely shunted, the fourth arc C^1-M^3 is the last to be extinguished.

Fig. 9 shows a particular disposition of the various chimneys and blast pipes corresponding to that of Fig. 6, a disposition which can equally be adopted in the devices corresponding to the diagrams of Figs. 7 and 8.

Instead of constituting the system of electrodes in the form of a forked member whose extremities are provided with the auxiliary electrodes as shown in the preceding figures, a system formed by a straight or bent bar as shown in Figs. 10 and 11 may also be used. In all these systems of electrodes C, the conductor coupling 25 together the various electrodes may be protected by an electric insulating material.

Having now particularly described and ascertained the nature of my said invention and in what manner the same is to be performed, I desire 30 to declare that what I claim is:

1. A circuit-breaker comprising, in combination, two contacts relatively movable to produce an arc at break; two fixed, electrically interconnected auxiliary electrodes spaced laterally from each other in the plane of movement of said contacts, and having their free ends directed toward the latter; and means to project a blast of extinguishing fluid past said relatively movable contacts toward said fixed auxiliary electrodes and 40 transversely to the path of movement of said contacts, to project the arc extending between said relatively movable contacts into contact with said fixed auxiliary electrodes, thereby to divide said arc into two separate arcs, each extending parallel to the direction of said blast between one of said relatively movable contacts and one of said auxiliary electrodes, said separate arcs being thus readily extinguished by said blast.

2. A circuit-breaker comprising, in combination, two contacts; two electrically interconnected fixed auxiliary electrodes spaced laterally from each other in the plane of said contacts and having their free ends directed toward the latter; a conjuncting conductor positioned between said contacts in the plane of the latter, said contacts being relatively movable into and out of contact with said conjuncting conductor, to produce two arcs at break, each extending between said conjuncting conductor and one of said movable contacts; and means to project a blast of extinguishing fluid past, and transversely to, the path of movement of said relatively movable contacts and toward said fixed auxiliary electrodes, to project said two arcs extending between said two movable contacts and said conjuncting conductor into contact with said two fixed auxiliary electrodes respectively, thereby to short-circuit said arcs and extinguish their inner branches, their outer branches, extending substantially parallel to the direction of said blast, being thus readily extinguished by the latter.

3. A circuit-breaker comprising, in combination, two contacts; a plurality of electrically interconnected fixed auxiliary electrodes spaced laterally from each other in the plane of said contacts

and having their free ends directed toward the latter; a plurality of conjuncting conductors positioned between said contacts in line with the latter and suitably spaced from each other, said contacts being relatively movable into and out of contact with said conjuncting conductors to produce as many arcs at break as there are fixed auxiliary electrodes, the end arcs each extending between one of said contacts and the adjacent conjuncting conductor and the intermediate arcs each extending between two adjacent conjuncting conductors; and means to project a blast of extinguishing fluid past, and transversely to the path of movement of said contacts, and toward said fixed auxiliary electrodes, to project said arcs, one into contact with each of said fixed auxiliary electrodes, thereby to short circuit and extinguish said arcs.

4. A circuit-breaker comprising, in combination, two contacts relatively movable to produce an arc at break; two fixed, electrically interconnected auxiliary electrodes, spaced laterally from each other in the plane of movement of said contacts and having their free ends directed toward the latter; means to project a blast of extinguishing fluid past, and transversely to the path of movement of said contacts and toward said fixed auxiliary electrodes, to project the arc produced between said contacts and extending transversely to the direction of said blast, into contact with said fixed auxiliary electrodes, thereby to divide said arc into two separate arcs extending parallel to the direction of said blast between one of said contacts and one of said auxiliary electrodes respectively, thereby facilitating extinction of said arc; and a resistance connecting said auxiliary electrodes to one of said contacts to accelerate the extinction of said arc.

5. A circuit-breaker comprising, in combination, a conduit; a chimney; a partition extending within and lengthwise of said chimney; communicating passages leading from said conduit and opening into said chimney at opposite sides of said partition; means to project a blast of extinguishing fluid through said conduit, said passages and said chimney upon both sides of said partition; two contacts located in said conduit and relatively movable transversely to the direction of said blast to produce an arc at break; two auxiliary electrodes electrically interconnected and situated in said chimney upon opposite sides, respectively, of said partition, said electrodes being insulated from said relatively movable contacts.

6. A circuit-breaker comprising, in combination, a conduit; a chimney; a partition extending lengthwise of said chimney; communicating passages leading from said conduit and opening into said chimney at opposite sides of said partition; means to project a blast of extinguishing fluid through said conduit, said passages and said chimney upon both sides of said partition; two contacts located in said conduit and relatively movable transversely to the direction of said blast to produce an arc at break; two auxiliary electrodes electrically interconnected and situated in said chimney upon opposite sides respectively of said partition, said electrodes being insulated from said relatively movable contacts; two fixed electrodes located between said auxiliary electrodes and said relatively movable contacts, and connected one to each one of the latter; and two intermediary electrodes between said fixed electrodes and said auxiliary electrodes, said intermediary electrodes being each connected to one

of said relatively movable contacts through suitable resistances.

7. A circuit-breaker comprising, in combination, a conduit; a chimney; a partition extending lengthwise of said chimney; communicating passages leading from said conduit and opening into said chimney at opposite sides respectively of said partition; means to project a blast of extinguishing fluid through said conduit, said passages and said chimney upon both sides of said partition; two contacts located in said conduit and relatively movable transversely to the direction of said blast to produce an arc at break; two auxiliary electrodes electrically interconnected and situated in said chimney upon opposite sides respectively of said partition; two fixed electrodes located between said auxiliary electrodes and said relatively movable contacts and connected one to each one of the latter; and two intermediary electrodes between said fixed electrodes and said auxiliary electrodes; and a resistance connecting said auxiliary electrodes with one of said relatively movable contacts.

8. A circuit-breaker comprising, in combination, two contacts; a conjuncting conductor positioned between said contacts in the plane of the latter; said contacts being relatively movable into and out of contact with said conjuncting conductor to produce two arcs at break, each extending between said conjuncting conductor and one of said movable contacts; two systems of auxiliary electrodes insulated, one system from the other and from said movable contacts, each system comprising two auxiliary electrodes interconnected and spaced laterally from each other in the plane of movement of said contacts; and means to project a blast of extinguishing fluid past, and transversely to the path of movement of said contacts, to project the arcs produced transversely to the direction of said blast between said contacts, into contact with said auxiliary electrodes, thus to divide said arcs into a plurality of individual arcs extending substantially parallel to said blast, thereby facilitating their extinction by said blast.

9. A circuit-breaker comprising, in combination, two contacts; a conjuncting conductor positioned between said contacts in the plane of the latter, said contacts being relatively movable into and out of contact with said conjuncting conductor to produce two arcs at break, each extending between said conjuncting conductor and one of said movable contacts; two systems of auxiliary electrodes insulated one system from the other and from said movable contacts, each system comprising two auxiliary electrodes; two fixed electrodes located between said auxiliary electrodes and said movable contacts and connected one to each of the latter; an intermediary electrode between said fixed electrodes and said auxiliary electrodes, said intermediary electrode being connected to one of said relatively movable contacts through a suitable resistance; and means to project a blast of extinguishing fluid past, and transversely to the path of movement of, said contacts, to project the arcs produced transversely to the direction of said blast between said contacts, into contact with said fixed electrodes, said

intermediary electrode and said auxiliary electrodes, thus to divide said arcs into a plurality of individual arcs extending substantially parallel to said blast, thereby facilitating their extinction by said blast.

10. A circuit-breaker comprising, in combination, two contacts; a conjuncting conductor positioned between said contacts in the plane of the latter, said contacts being relatively movable into and out of contact with said conjuncting conductor to produce two arcs at break, each extending between said conjuncting conductor and one of said movable contacts, respectively; two systems of auxiliary electrodes insulated one system from the other, each system comprising two auxiliary electrodes, having their free ends directed towards said contacts; two fixed electrodes located between said auxiliary electrodes and said movable contacts and connected one to each of the latter; an intermediary electrode between one of said fixed electrodes and one of said auxiliary electrodes, said intermediary electrode being connected to one of said fixed electrodes, and one of said systems of auxiliary electrodes being insulated and the other connected by two resistances to the other of said fixed electrodes on the one hand and to said conjuncting conductor on the other hand; and means to project a blast of extinguishing fluid past, and transversely to the path of movement of said contacts, to project the arcs produced transversely to the direction of said blast between said contacts, into contact with said fixed electrodes, said intermediary electrode and said auxiliary electrodes, thus to divide said arcs into a plurality of individual arcs extending substantially parallel to said blast, to facilitate their extinction by said blast.

11. A circuit-breaker comprising, in combination, two contacts; a conjuncting conductor positioned between said contacts, in the plane of the latter, said contacts being relatively movable into and out of contact with said conjuncting conductor to produce two arcs at break, each extending between said conjuncting conductor and one of said movable contacts respectively; two systems of auxiliary electrodes insulated one system from the other, each system comprising two auxiliary electrodes having their free ends directed towards said contacts; two fixed electrodes located between said auxiliary electrodes and said movable contacts and connected each to one of the latter, both of said systems of auxiliary electrodes being connected each to one of said relatively movable contacts through a suitable resistance; and means to project a blast of extinguishing fluid past, and transversely to the path of movement of said contacts, to project the arcs produced transversely to the direction of said blast between said contacts, into contact with said fixed electrodes and said auxiliary electrodes, thus to divide said arcs into a plurality of individual arcs extending substantially parallel to the direction of said blast, whereby to facilitate their extinction by the latter.

ANDRÉ CLERC.
